UNITED STATES PATENT OFFICE.

JOHN LOUIS SABBATH, OF MONTREAL, QUEBEC, CANADA.

DESIGN FOR A BRACELET.

60,377.

Specification for Design.

Patented Feb. 7, 1922.

Application filed September 28, 1921. Serial No. 503,988. Term of patent 7 years.

To all whom it may concern:

Be it known that I, JOHN LOUIS SABBATH, a British subject, residing at Montreal, in the Province of Quebec, in the Dominion of Canada, have invented a new, original, and ornamental Design for Bracelets, of which the following is a specification, reference being had to the accompanying drawing, forming part thereof.

In the accompanying drawing:

Figure 1 is a plan view showing the present design as applied to a bracelet.

Fig. 2 is an enlarged detail view showing the configuration of the disk-like members.

The disk-like intermediate member shown in the accompanying drawing has the ap-

pearance of a continuous coil. This appearance may be produced by forming the member with spiral grooves, or by winding a comparatively fine wire thereon. However, as far as the present invention is concerned it may be produced by any means.

In the present invention the disk-like members intermediate the globe-like members are of substantially the same diameter as the globular members and as so arranged produce a very pleasing and distinctive effect.

I claim:—

The ornamental design for a bracelet as shown.

JOHN LOUIS SABBATH.
